(57) **CLAIM**

The ornamental design for a lighting fixture, as shown and
described.

DESCRIPTION

FIG. 1 is a perspective view of the new design;
FIG. 2 is a front view of the design of FIG. 1;
FIG. 3 is a side view of the design of FIG. 1;
FIG. 4 is a rear view of the design of FIG. 1;
FIG. 5 is a top view of the design of FIG. 1; and,
FIG. 6 is a bottom view of the design of FIG. 1.
The broken lines shown on the drawings depict portions of
the lighting fixture that form no part of the claimed design.
